PROJECTILE INTERCEPTING MEANS

Joseph Kalnitz, Buffalo, N. Y.

Application December 27, 1943, Serial No. 515,712

8 Claims. (Cl. 114—240)

This invention relates to novel means for defending and protecting marine vessels against projectiles and, more particularly, against projectiles of the torpedo type, both submarine and aerial.

According to the present invention apparatus is provided which, when not in use, lies closely alongside of the vessel with which it is associated. However, the apparatus is provided with automotive means by virtue of which it projects itself into a position spaced laterally from the vessel to intercept torpedoes traveling toward the vessel either above or below the surface of the water. Further, according to the present invention, the interception of projectiles is accomplished in a novel manner, owing in part but not entirely to a novel way in which the interception means is suspended or supported.

The apparatus of the present invention is further characterized by the fact that the intercepting means is of proper buoyancy to automatically maintain a proper elevational position, in which position it is disposed to intercept a projectile approaching the vessel with which it is associated, whether such projectile is a torpedo of the type traveling a short distance beneath the surface of the water or whether it is of the type which travels just above the water. According to one form of the invention the momentum of the projectile is converted in part into a turning moment acting upon the apparatus and in part into a component tending to move the apparatus toward the vessel. The latter component is not harmful, since the inertia or drag of the apparatus when it is struck by a torpedo is adequate to prevent any material actual movement of the apparatus in the direction of the vessel.

As an example of the application of the principles of my invention, the following description and the accompanying drawing set forth apparatus wherein a remotely controlled pilot boat device renders the torpedo intercepting means automotive. However, it is within the purview of the present invention to employ auxiliary craft in this capacity, and especially in the case of large vessels like battleships and cruisers, patrol boats or like craft carrying crews may be used to provide tractive force for the intercepting means.

The accompanying drawing and the ensuing specification delineate an exemplary form of the principles of the present invention, but it is to be understood that the spirit and scope of the

invention is not limited thereto, or otherwise than as defined in the appended claims.

In the drawing:

Fig. 1 is a top plan view of a vessel equipped with apparatus according to the present invention;

Fig. 2 is a front elevational view, with the apparatus shown in cross section;

Fig. 3 is a fragmentary side elevational view of the intercepting apparatus of Figs. 1 and 2; and

Fig. 4 is an enlarged fragmentary side elevational view of the front end of such intercepting apparatus.

Throughout the several figures of the drawing like characters of reference denote like parts and in Figs. 1 and 2 the numeral 10 designates a vessel with which one form of the apparatus of my invention is shown associated. The intercepting apparatus comprises a series of supporting elements 11 which in the illustrated form comprise tubular elements having their ends sealed to render them buoyant. However, timbers or other naturally buoyant means may be employed with equal effect. The several supporting elements 11 are articulated as at 12 and the connections are intended to be conveniently detachable in any desired manner. This permits ready replacement of a unit that has been damaged in any way and also permits ready assembly and disassembly when the apparatus is to be applied to or removed from a vessel.

When the apparatus is in position to protect a vessel the several supporting elements 11 extend in end to end relation, parallel to the vessel, and are spaced substantially therefrom, all as shown at the right hand or starboard side of the vessel 10 in Fig. 1. This relationship is also illustrated in Fig. 2. Each of the longitudinal supporting elements 11 has a series of spaced vertical bars or rods 13 fixed thereto and longitudinal tie rods 14 fixed to the bars or rods 13, by welding or in any other convenient manner, hold the vertical bars or rods 13 in fixed spaced relation.

It will be noted from Fig. 2 that the bars or rods 13 extend both above and below the surface of the water and terminate in arcuate portions 15 which are directed away from the vessel with which the apparatus is associated. It is preferred to extend bars or rods 13 further below the water than above. This automatically disposes the center of gravity of the assembly below the supporting elements 11 and serves to position the device automatically in the erect position illustrated. If desired, however, the proportionate lengths above and below the water may be freely

varied and weight means may be employed to dispose the apparatus vertically.

When a projectile strikes the screen formed by the elements 13 and 14 it tends to rotate the assembly about the supporting elements 11 and, although the nose of the projectile will usually extend through the screen and become lodged therein, the arcuate portions 15 will in any event prevent any projectile which comes against the device from passing it upon rotation of the assembly. In the case of a torpedo much more often than not the detonator in the nose thereof will not strike a bar 13 or a tie rod 14, and accordingly the torpedo will not explode. However, even in the event of explosion, the screen 13, 14 will be spaced sufficiently from the vessel 10 to prevent serious damage, although some effects of the explosion may result. Sections of the screen 13, 14 which may be destroyed by explosion may be readily replaced, as heretofore suggested.

The assemblies, comprising a series of articulated supporting elements 11 and their associated bars 13 and tie rods 14, are self-positioning and to this end the forward end of the forward element 11 is connected to a propulsion device designated generally 20 in Figs. 1 and 4. As appears best in Fig. 4, a bail 21 may be pivotally connected to the forward end of forward supporting element 11 and to the rear of the propulsion device. The latter may have any suitable motor or engine (not shown) for driving a screw propeller 22 and no steering of the propulsion device is required, so that simple engine starting and stopping or clutching and de-clutching means may be provided, such means being remotely controlled from the vessel 10 by electrical conduits, flexible chain means, Bowden wires, cables or any other suitable means. Since no invention is claimed for the specific engine or motor means or the specific engine or motor control means they are not illustrated or described herein in detail.

In the illustrated example each propulsion device is pivotally attached, as at 24, to the end of an arm or boom 25 which is in turn pivotally attached to the bow of the vessel, as at 26. In Fig. 1 the torpedo intercepting means is shown in an inactive position at the port side of the vessel. If the propulsion device 20 at this side of the vessel be activated, the entire assembly moves forwardly with respect to the vessel but, being constrained to move in an arcuate path defined by the boom 25. The series of intercepting elements moves outwardly away from the vessel until the assembly reaches a position corresponding to that illustrated at the starboard side of the vessel in Fig. 1.

Cables or guy wires 28 limit the degree of forward movement of the propulsion devices 20 and arrest their relative forward movement when the booms are in positions substantially normal to the vessel. Rear cables or guy wires 29 prevent the tails of the assemblies from drifting away from the vessel under various navigational conditions.

What is claimed is:

1. Marine projectile intercepting apparatus for association with a vessel comprising, an elongate projectile intercepting means, a boom adapted to be pivotally attached at its opposite ends to the bow of a vessel and to the forward end of said means, and a tractive device at the forward portion of said intercepting means, said tractive device including propulsion means and

a prime mover therefor, whereby operation of said tractive device swings said boom forwardly to move the intercepting means away from a vessel to be held spaced therefrom by said boom and whereby continued operation of said tractive means eliminates drag on the vessel by the intercepting means.

2. Marine projectile intercepting apparatus comprising a boom adapted to be pivotally attached at one end to the bow of a vessel and swingable horizontally from a rearwardly extending position substantially alongside said vessel to a position substantially normal thereto, elongate projectile intercepting means pivotally attached at a forward end to the opposite end of said boom, and motive means acting against said opposite end of said boom and the forward end of the intercepting means to move said boom from its rearwardly extending position and thereby space said intercepting means from the vessel to prevent passage of projectiles to the vessel.

3. A marine projectile intercepting barrier comprising an elongate buoyant supporting element, and a series of longitudinally spaced vertically extending bars extending both above and below said supporting element.

4. A marine projectile intercepting barrier comprising a series of elongate buoyant supporting elements connected in end to end relation, each of said supporting elements having a series of longitudinally spaced vertically extending bars extending both above and below said supporting element.

5. A marine projectile intercepting barrier comprising an elongate buoyant supporting element, a series of longitudinally spaced vertical bars extending both above and below said buoyant supporting element, and vertically spaced longitudinal bars rigidly connected with said vertical bars to prevent their longitudinal displacement under impact.

6. A marine projectile intercepting barrier comprising an elongate buoyant supporting element and a series of longitudinally spaced vertical bars extending both above and below said supporting element, the terminal portions of said bars being formed substantially into semi-circles, said semi-circular formations being adapted to extend away from a vessel to be protected whereby to serve as projectile restraining troughs upon rotation of said barrier about its buoyant supporting element.

7. A marine projectile intercepting apparatus comprising a boom adapted to be pivotally attached at one end to the bow of a vessel and swingable horizontally from a rearwardly extending position substantially alongside said vessel to a position substantially normal thereto, elongate projectile intercepting means pivotally attached at a forward end to the opposite end of said boom, and motive means acting against said opposite end of said boom and the forward end of the intercepting means to move said boom from its rearwardly extending position and thereby space said intercepting means from the vessel to prevent passage of projectiles to the vessel, said intercepting means comprising an elongate buoyant supporting element and relatively rigid intercepting barriers extending both above and below said supporting elements.

8. Marine projectile intercepting apparatus comprising a boom adapted to be pivotally attached at one end to the bow of a vessel and swingable horizontally from a rearwardly extending position substantially alongside said ves-

sel to a position substantially normal thereto, elongate projectile intercepting means pivotally attached at a forward end to the opposite end of said boom, and motive means acting against said opposite end of said boom and the forward end of the intercepting means to move said boom from its rearwardly extending position and thereby space said intercepting means from the vessel

to prevent passage of projectiles to the vessel, said intercepting means comprising a series of elongate buoyant supporting members connected in articulated end to end relation, each supporting member having relatively rigid intercepting barriers extending both above and below said supporting elements.

JOSEPH KALNITZ.
